UNITED STATES PATENT OFFICE.

EBERHARD KOCH, OF NEW ORLEANS, LOUISIANA, ASSIGNOR OF ONE-HALF
TO CHARLES J. ALLEN, OF SAME PLACE.

WOOD-DISTILLING APPARATUS.

SPECIFICATION forming part of Letters Patent No. 367,413, dated August 2, 1887.

Application filed March 1, 1887. Serial No. 239,328. (No model.)

To all whom it may concern:

Be it known that I, EBERHARD KOCH, of New Orleans, in the parish of Orleans and State of Louisiana, have invented certain new and useful Improvements in Wood-Distilling Apparatus; and I do hereby declare the following to be a full, clear, and exact description of the invention, such as will enable others skilled in the art to which it appertains to make and use to the same.

My invention relates to an improved apparatus for the distillation of wood to remove the alcoholic and resinous elements therefrom and carbonize the fiber.

Letters Patent of the United States numbered 316,794, dated April 28, 1885, were granted to me for an improved apparatus to effect the distillation of wood, remove and condense volatile products, and carbonize the remaining structural fiber without detriment to the same, and effect the process in an economical and expeditious manner.

It has been found in practice that the general features of construction of the patented device just mentioned are operative to a degree. Continuity of effective operation of the apparatus, however, is seriously impaired by the accumulation of tarry matter in the neck and throughout the interior surface of the stand-pipe and horizontal branch that leads to the condenser-coil.

The object of my present invention is to overcome the tendency to deposit and carbonize resin in the stand-pipe and its horizontal branch, and thus permit continuous effective action of the distilling apparatus, and also to furnish a means for the easy inspection of the parts liable to stop up, to permit such an examination to be made without arresting the progress of the work by a removal of pipes or other important fixtures.

With these objects in view my invention consists in certain features of construction and combinations of parts, that will be hereinafter described, and pointed out in the claims.

Referring to the drawings making a part of this specification, Figure 1 is a side elevation, in section, of a distilling apparatus with the improved features embodied. Fig. 2 is an enlarged view of the stand-pipe and its branch

to the condenser-coil in longitudinal section through its axial center. Fig. 3 is a front elevation of the apparatus.

A represents a retort, preferably made of sheet plate metal, having an outer masonry envelope, B, that completely incloses the retort.

A furnace, C, is provided at the lower front portion of the retort A, having a horizontal flue, D, extending rearwardly beneath the retort, and thence vertically to connect with the chimney - stack E. A superheating coiled pipe, F, is located in the flue D, and is made to connect its front end, F', with a steam-generator. (Not shown.) The rear end of the coil F is upwardly extended to attach to the retort A. The front end of the retort A is provided with a door, G, which is made steam-tight by any suitable means. The masonry that surrounds the retort also has a door, H, of a size corresponding to the dimensions of the retort, to permit the ready removal of the box-trucks W, that are supported upon wheels to run upon a track placed upon the lower surface of the retort. One or more of these movable trucks are furnished, they being designed to contain the wood to be operated upon. The sides of the trucks may be slatted or otherwise made open for the free admission of steam to the wood placed in them.

A duplicate retort, A', is constructed in front of the retort proper, subserving the purpose of a cooling-chamber, into which the trucks W are removed when the process of carbonization is completed. The second chamber or duplicate retort is made air-tight, and to permit trucks placed in this chamber to be removed therefrom a transfer - table, N, is placed in front of the duplicate retort to receive the truck upon it. This transfer-table, resting upon a transverse track situated in a lower plane than the tracks in retort A, allows the removal of the trucks when properly cooled from duplicate retort to the open air for storage of their contents in a proper magazine.

A stand-pipe, I, is fixed into the top surface of the retort A, and is made to extend upwardly a proper distance to connect with a laterally-extended conduit-pipe, I', that has an outlet, I'', to which the condenser-coil J is se-

cured. The front and rear ends of the horizontal conduit-pipe I' are furnished with removable bonnets or lids made to close steam-tight and be secured by a means that will allow them to be detached readily, and thus give access to the interior of the pipe to cleanse it when required. The vertical stand-pipe I is also provided with a lid, K, to close an outlet made at the top of the stand-pipe for admission to its interior.

In order to prevent a deposit of carbon upon the horizontal conduit-pipe I', a water-jacket, I², is secured in position to envelop the conduit-pipe I', as shown in Figs. 2 and 3. This exterior jacket may be made open at the top, as a trough, or closed to form a close pipe. A proper space to allow the introduction of a cold-water current through the water-jacket I² is made to intervene between the pipe and inner surface of the jacket, as shown in Fig. 2.

From the under side of the lid K the chains m are suspended to hang vertically in the pipe I. Upon the lower portion of the looped chains m the wire screen n is attached to form a perforated abutment, upon which impinge the vertically-ascending gases evolved by action of the superheated steam upon the wood inclosed in the retort. Several thicknesses of the screen-wire may be used to furnish a sufficiently-stable impinging surface for the volatile vapors that are carried upward by the influx of the volume of superheated steam from the inlet-pipe D' of the coil D. (See Fig. 1.) A steam-gage, L, is fixed to indicate steam-pressure in the retort A.

As the separation of the elementary products of wood carbonized by being subjected to the joint action of heat and superheated steam will evolve considerable uncondensable gas, which gas it is important to remove from the condenser-coil J, I connect a bent gas-pipe, U, that forms a U-shaped trap, which is preferably connected to a four-way on the lower end of the coil J, and thence leads the contents of the coil to a receiving-tank. The trap will prevent any escape of the gaseous products, which may be conducted off by a pipe connected to either of the vertical branches T' T² of the four-way T, which are provided to lead these gaseous products away.

The gas may be utilized as a fuel for steam-generation or be stored in a gasometer, as desired.

In operation the trucks W are loaded and are introduced into the retort A. The doors of the retort A are now secured steam-tight and fire started to heat the coil D. Steam is in-

troduced and superheated by contact with the hot coil. Its passage through the wood in the retort A will cause a permeation of the wood cells by this superheated steam, and a consequent abstraction of the alcoholic, albuminous, and resinous elements contained therein.

The pressure of a continued influx of steam will force the impregnated vapor to rise in the stand-pipe and filter through the screen-wire cloth in the stand-pipe I. This will remove the larger portion of the flaky carbon from the impregnated vapor, and its contact with the cooled surface of the horizontal conduit-pipe I' will throw down more of the tarry products in a liquid form. These may be withdrawn by a suitable pipe-connection and the condenser-pipe relieved of the heavy matter, which will have a tendency to choke it and prevent the free withdrawal of the lighter or alcoholic distillate, that is a valuable product of the carbonizing process just described.

Having fully described the improvement I have combined with my patented apparatus shown in Patent No. 316,794, what I claim as new, and desire to secure by Letters Patent, is—

1. In a wood-distilling apparatus, the combination, with a retort and condenser-coil, of a stand-pipe leading from the retort to the condenser-coil and having a loosely-depend wire screen adapted to be removed for cleansing purposes, substantially as set forth.
2. In a wood-distilling apparatus, the combination, with a retort, a stand-pipe, and condenser-coil, of a conduit connecting the stand-pipe and condenser-coil, and a water trough or jacket surrounding the conduit, substantially as and for the purpose set forth.
3. In a wood-distilling apparatus, the combination, with a sealed retort, of a stand-pipe and conduit-pipe communicating therewith, each provided with removable lids to give access to their interiors, substantially as set forth.
4. In a wood-distilling apparatus, the combination, with a sealed retort, of a stand-pipe having a removable lid on its top, and having chain-suspended screens, and horizontal conduit-pipe provided with a water-jacket and removable lids, substantially as set forth.

In testimony whereof I have signed this specification in the presence of two subscribing witnesses.

EBERHARD KOCH.
